Specification for Design.

Patented Mar. 18, 1919.

Application filed November 13, 1916. Serial No. 131,147. Term of patent 14 years.

To all whom it may concern:

Be it known that I, DAVID F. CREIGHTON, a citizen of the United States, and resident of Avalon, in the county of Allegheny and State of Pennsylvania, have invented a new, original, and ornamental Design for Metal Shingles, of which the following is a specification, reference being had to the accompanying drawing, forming part thereof.

Figure 1 is a plan view of a shingle, show-

ing my new design; Fig. 2 is a side elevation, and Fig. 3 is an end elevation of the same.

I claim:

The ornamental design for a metal shingle, as shown.

DAVID F. CREIGHTON.
